CLAIM

The ornamental design for a curved lighting fixture, as shown and described.

DESCRIPTION

FIG. 1 is a top perspective view of a curved lighting fixture showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a top perspective view of an alternative exemplary curved lighting fixture showing our new design having a translucent filing.

The curved lighting fixture is shown with a symbolic break in its length. The appearance of any portion of the curved lighting fixture between the jagged break lines forms no part of the claimed design.

The broken lines in the drawings illustrate portions of the curved lighting fixture which form no part of the claimed design.
